APPARATUS FOR FORMING WINDOW OPENINGS IN TRAVELING WEBS

Adolph Potdevin, Garden City, N. Y., assignor to
 Potdevin Machine Company, Brooklyn, N. Y.,
 a corporation of New York

Application December 18, 1936, Serial No. 116,538

6 Claims. (Cl. 164—28)

This invention is directed to an improvement in the window forming mechanism of my Patent No. 1,995,719 of March 26, 1935, and has for one of its objects the provision of means for insuring the same speed for die and web at the instant the cross cut is made at the ends of the window opening.

A further object of my invention is the provision of means whereby the length of the window opening may be varied.

In the accompanying drawings:

Fig. 1 is an elevational view of an embodiment of my invention;

Fig. 2 is a plan view of the apparatus of Fig. 1;

Fig. 3 is a detail;

Fig. 4 is a view somewhat enlarged with respect to Fig. 1 of the speed controlling mechanism;

Fig. 5 is a plan view of the die and its cooperating anvil;

Fig. 6 is a view on the line 6—6 of Fig. 4; and

Fig. 7 is a view of a paper bag of the window type.

As briefly pointed out above this invention is directed to improving machines for providing window openings in a traveling web of paper. The window opening of course may be of any desired size but in any event a section of paper must be removed from the web of paper as the same is advancing through the machine to where the windows are applied, for instance. The die is of the rotary type and cooperates with a rotary anvil, both the die and anvil rotating continuously during the operation of the machine and in the forming of the window openings in the traveling web. It is obviously advantageous to insure that the paper and the die travel at the same speed when the die makes the cross cuts at the ends of the window opening, travel of the paper web and the die at different speeds during these stages of forming the window opening tending to cause the paper to tear, and particularly if the paper is traveling at a faster speed than the die.

Referring to the drawings in detail, I designates the roll of paper from which the paper web is unrolled and drawn continuously through the machine. For convenience the web of paper will be designated 2. An inspection of Fig. 1 of the drawings shows that the web 2 is first passed around an idler roller 3 and from thence goes between a rotary die 4 and rotary anvil 5, then about opposite sides of rollers 6 and 7 and past ejecting rollers 8, idlers 9, 10, 11, etc., out of the machine. I have deemed it unnecessary in this

application to show the mechanism by which the windows are applied to the window openings in the paper web inasmuch as the same constitutes a part of the subject matter of my Patent No. 1,995,719 above referred to. The die 4 comprises 5 sides 4' and end knives 4''. The leading end knife makes a transverse cut in the paper, the sides 4' slit the paper from there until the trailing end knife makes its transverse cut.

As pointed out above it is desirable in a machine for cutting window openings in a continuously moving or advancing web to provide that the speed of the die which forms the opening shall be the same as the speed of the paper when the transverse cuts are made at the ends of the 15 window opening.

The rotary die 4 in the present instance is driven at a predetermined speed from gear 12 through intermediate gear 13 and gear 14, the latter being on the shaft 15 which carries the 20 die. The die cooperates with rotary anvil 5 which is driven through gear 15' driven off shaft 15.

As explained in connection with my Patent No. 1,995,719, above referred to, the anvil 5 is 25 made adjustable so as to accommodate the machine to dies 4 of varying diameters, and so that the anvil may be moved away from the die to permit of threading the machine initially.

The present invention provides that one of the 30 control rollers 6 which engages the paper web, as above explained, shall be moved intermittently and automatically to vary the speed of the web 2 at the instant the leading end knife 4'' makes its transverse cut, and at the instant the trailing 35 end knife 4'' makes its transverse cut, so that at these times the die and paper will be moving at the same speed. This roller 6 is mounted on an arm 16 pivoted on the center about which the roller 7 rotates, the arm 16 being one arm 40 of a bell crank lever, the other arm of which is designated 17 and is attached to an upwardly extending rod 18.

The upper end of the rod 18 has an adjustable slot and pin connection with the arm 19 of a 45 bell crank lever which is pivoted at 20 to the frame of the machine. The other arm 21 of this bell crank lever carries a cam follower 22 cooperating with a cam 23, the latter being mounted on the shaft 24 which for the purposes of this invention may be considered the drive shaft of the machine. The cam 23 is made up of two plates 25 and 26 which are bolted to each other by bolts 27, the plate 25 being provided with active surface 28, the plate 26 with active sur- 50 55

face 28. The plates are slotted to permit of their relative adjustment circumferentially of the shaft 24 to vary the spacing of the active surfaces 28 and 29 to take care of window openings of different lengths. The cam follower is held against the cam by a spring—not shown.

It will be appreciated from the foregoing that in operation of the machine the cam surfaces 28 and 29 will cause the bell crank lever arm 19 to be rocked about the pivot 20 to impart a movement to the control roller 6 from the full line position to the dotted line position of Fig. 4, the roller snapping back to full line position as the cam follower rides off the high spot of the cam. It will be appreciated that the cam plates 25 and 26 are so adjusted relatively to each other that this vibration of the roller 6 takes place at the leading end of the window opening and at the trailing end. The primary purpose of this arrangement is to effect a momentary variation in the linear speed of the web when the transverse cuts are made so that the die and web on these occasions are traveling at the same speed to insure a clean transverse cut of the web at the ends of the window opening. Intermediate the ends of the window opening the paper may travel at a much higher speed than the die, the sides of the die slitting the paper lengthwise. This, it will be apparent, permits window openings to be cut which are much longer than the die, so that the same die may be used for openings of different lengths.

In Fig. 7 the window opening has been designated 30 and the ends of the window opening 31 and 32. The sides of the window opening are produced by the side knives 4' and the ends by the end knives 4''. The shape and size of the opening may be varied, as will be understood.

It is to be understood that various changes and modifications may be made in the details of the structure herein illustrated and described without departing from the spirit and scope of my invention.

What I claim is:

1. In a machine for providing window openings at intervals along the length of an advancing web, the combination of a rotary cutter, a cooperating rotary anvil, a roller engaging the web beyond the cutter and anvil, and means for displacing said roller intermittently, to change the speed of the web to the peripheral speed of said rotary cutter at the ends of the window opening.

2. In a machine for providing window openings at intervals along the length of an advancing web, the combination of a rotary cutter, a cooperating rotary anvil, a bell crank lever, a roller carried by said lever about which the web passes, an adjustable cam, means actuated by said cam for rocking said bell crank lever to displace said roller and web intermittently to vary the speed of

said web to that of the cutter at the ends of the window opening.

3. In a machine for providing window openings at spaced intervals along the length of an advancing web of material, the combination of means for advancing the web, a rotary cutter and a cooperating anvil in the path of travel of said web, a bell crank lever, a roller in contact with said web carried by one arm of said bell crank lever, a rod connected to the other arm of said bell crank lever, a second bell crank lever at the other end of said rod, a cam for actuating said last mentioned bell crank lever to rock the first mentioned lever to displace said roller and web to vary the speed of the web to that of the punch at each end of the window opening.

4. In a machine for providing window openings at spaced intervals along the length of an advancing web of material, the combination of means for advancing the web, a rotary cutter comprising side knives and transverse end knives, in the path of travel of said web, a bell crank lever, a roller contacting with said web carried by one arm of said bell crank lever, a rod connected to the other arm of said bell crank lever, a second bell crank lever at the other end of said rod, a cam for actuating said last mentioned bell crank lever, said cam having adjustable cam surfaces adapted to rock the first mentioned lever to displace said roller and web intermittently to effect a change in the web speed to that of the cutter at the instant of operation of said transverse knives.

5. In a machine for providing window openings at intervals along the length of an advancing web, the combination of a rotary elongated cutter, a cooperating rotary anvil, means for advancing said web between the cutter and anvil at a different linear speed from that of the said cutter, and means for displacing the web there-by automatically to vary its speed at the beginning of the operation of the cutter and for again displacing the web to vary its speed at the end of the operation of the cutter to effect movement of the web at those instants at the same linear speed as that of the said cutter.

6. In a machine for providing window openings at intervals along the length of an advancing web, the combination of a rotary die having side knives and end knives, a cooperating rotary anvil, means for passing the web between the anvil and cutter at a different linear speed from that of the cutter during the operation of said side knives, and means for displacing the advancing web at the time of operation of the leading end knife and again at the time of operation of the trailing end knife, to effect movement of the web at those instants at the same speed as that of the cutter.

ADOLPH POTDEVIN.
